UNITED STATES PATENT OFFICE.

HENRY CLEMONS, OF CASTALIA, OHIO.

DESIGN FOR A FRAME FOR LIFTING-JACKS.

SPECIFICATION forming part of Design No. 27,295, dated July 20, 1897.

Application filed January 19, 1897. Serial No. 619,810. Term of patent 3¹ years.

To all whom it may concern:

Be it known that I, HENRY CLEMONS, of Castalia, in the county of Erie and State of Ohio, have invented a certain new and useful 5 Design for Lifting-Jack Frames; and I do hereby declare the following to be a full, clear, and exact description of the invention, such as will enable others skilled in the art to which it pertains to make and use it, reference being had to the accompanying drawing, which forms part of this specification.

This invention relates to a lifting-jack frame of new and original design, as disclosed by the accompanying drawing, which presents 10 a perspective view of the same.

The new and original design consists of the rectangular base-piece A, from which is raised centrally the elongated upright B, and which is slotted or recessed downwardly from 15 its upper end, as shown at C, the slot or recess terminating a short distance above the upper end of the angular inclined brace mem-

bers D, which are on opposite sides of upright B, and which have downward divergence to opposite ends of base A.

The upper slotted portion of upright B is slotted at F, and intersecting with this slot are the horizontal slots G, the latter being three in number, and the combined slots F and G outlining the letter E.

The essential features of the design are base A, elongated upright B, slotted downward from its upper end, the slotted upper portion of the upright formed with an E-shaped recess, and the inclined brace members D.

What I claim is—

The design for a lifting-jack frame, substantially as herein shown and described.

In testimony whereof I affix my signature in presence of two witnesses,

HENRY CLEMONS.
